WATER SKIING VEHICLE

Edwin L. Fellerman, 40 48th St.,
Weehawken, N.J. 07087

Filed May 13, 1968, Ser. No. 11,893

Term of patent 14 years

U.S. Cl. D71—1
Int. Cl. D12—06

FIG. 1

FIG. 4

FIG. 5

FIGURE 1 is a perspective view of a water skiing vehicle showing the novel design;

FIGURE 2 is a side elevational view thereof;

FIGURE 3 is a plan view thereof;

FIGURE 4 is a front elevational view thereof;

FIGURE 5 is a rear elevational view thereof.

The dominant features of my design reside in the portions shown in full lines.

The cross hatched shading on portions of the surfaces of the circular shroud in all figures is understood to represent the continuous appearance of that element over the entire area shown.

I claim:

The ornamental design for a water skiing vehicle, substantially as shown and described.
